UNITED STATES PATENT OFFICE.

JULIAN KENNEDY, OF PITTSBURGH, PENNSYLVANIA.

ROLLING-MILL.

1,261,548.

Specification of Letters Patent.

Patented Apr. 2, 1918.

Original application filed April 21, 1916, Serial No. 92,614. Divided and this application filed August 24, 1917. Serial No. 187,955.

To all whom it may concern:
Be it known that I, JULIAN KENNEDY, a citizen of the United States, residing at Pittsburgh, Allegheny county, Pennsylvania, 5 have invented a new and useful Improvement in Rolling-Mills, of which the following is a full, clear, and exact description, reference being had to the accompanying drawings, forming part of this specification, 10 in which—

Figure 1 is an end view of a portion of a mill embodying my invention;

Fig. 2 is an end elevation of the cylinders for operating the roll spindles;

15 Fig. 3 is a section on the line III—III of Fig. 2; and

Fig. 4 is a section on the line IV—IV of Fig. 3.

My invention has relation to rolling mills 20 and more particularly to novel supporting means for the driving spindles of a three-high mill. The object of my invention is to provide a supporting system for these spindles which will also provide means whereby 25 the angle of the spindles may be shifted to suit the adjustment of the rolls.

The present application is a division of my pending application Serial No. 92,614, filed April 21, 1916.

30 Referring to the accompanying drawings, in which I have illustrated a preferred embodiment of my invention, the numerals 2, 3 and 4 designate, respectively, the top, middle and bottom rolls of a three-high rolling 35 mill. 5, 6 and 7 designate, respectively, the driving spindles for the said rolls, these being connected to the roll shafts by any usual or suitable form of coupling 8, which will permit of angular movement of the spindles 40 relatively to the rolls. The spindles are connected by similar couplings 9 with driving shafts 10, extending into the housing 11 of the driving mechanism, which may also be of any usual or suitable character. 12 designates the usual screw-down mechanism for 45 the rolls, which may be actuated in any desired manner, as by the shaft 13, driven by the motor 14.

In accordance with my invention, I provide 50 each of the spindles 5, 6 and 7 with a yoke 15, in which it is rotatably supported, the yoke having laterally projecting trunnions 16, which engage bearings in the upper ends of piston rods 17 of hydraulic cylinders 18. Two of these rods are provided

for the yoke of each of the upper and middle spindles, each rod having its own actuating cylinders. The lower spindle has its yoke carried by a saddle 19, which, in turn, is carried by the piston 20 of a power cylinder 21.

It will be noted that all of the cylinders 18 open into a common chamber at the bottom provided with means by which connection may be made to any suitable source of approximately constant pressure. Also that the rods 17 for the middle and upper spindles are arranged so as to clear the spindle or spindles below the one which they support. Also that the plungers for the upper 70 and middle spindles are of less area than that of the single plunger for the lower spindle. By these arrangements, the weight of each spindle may be substantially counterbalanced and the spindle supported in its 75 adjusted position without interference with the other spindles, and the rolls effectively relieved of drag. The supporting action may be substantially the same in all positions of each spindle.

80 My invention provides a simple and efficient supporting system for the driving spindles of rolling mills, being especially adapted for use in large mills. By the provision of the yokes in which the spindles are 85 supported and which are, in turn, supported by the pistons and power cylinders, the angularity of the spindles can be readily changed to suit different roll adjustments.

I do not desire to limit myself to the particular construction, arrangement and combination of parts herein shown and described, since it will be obvious that changes may be made in the details thereof without departing from the spirit and scope of my invention as defined in the appended claims.

I claim:

1. In a rolling mill, the combination with a plurality of roll-driving spindles, arranged one above another of separate yokes 100 in which the spindles are rotatably supported, and a plurality of power cylinders arranged below the yokes, and having their plungers connected to and supporting said yokes, each yoke having its cylinder or cylinders and supporting connections, substantially as described.

2. In a rolling mill, the combination with a plurality of roll-driving spindles, arranged one above another of separate yokes in 110

- which the spindles are rotatably supported, and a plurality of power cylinders arranged below the yokes and having their plungers connected to and supporting said yokes, the
- 5 connections for the yokes above the lower yoke extending at opposite sides of the spindle or spindles below the yokes which they respectively support, substantially as described.
- 10 3. In a rolling mill, the combination with a plurality of roll-driving spindles, arranged one above another of separate yokes in which the spindles are rotatably supported, and a plurality of power cylinders ar-
- 15 ranged below the yokes, and having their plungers connected to and supporting said yokes, there being a single cylinder and plunger for the lower yoke, and two cylinders and plungers for each of the upper
- 20 yokes, substantially as described.
4. In a rolling mill, the combination with a plurality of roll-driving spindles, arranged one above another of separate yokes in which the spindles are rotatably support-
- 25 ed, and a plurality of power cylinders ar- ranged below the yokes, and having their plungers connected to and supporting said yokes, said cylinders having a common source of pressure supply, substantially as described.
- 30 5. In a rolling mill, the combination with a plurality of roll-driving spindles, arranged one above another of separate yokes in which the spindles are rotatably supported, and a plurality of power cylinders ar-
- 35 ranged below the yokes, and having their plungers connected to and supporting said yokes, said cylinders opening at their lower ends into a common pressure chamber, sub- stantially as described.
- 40 6. In a rolling mill, the combination with a roll-driving spindle, of a yoke or saddle in which the spindle is rotatably supported, and a power cylinder below the spindle, and having its plunger provided with an up- wardly extending member which is trun- nioned to the yoke or saddle, substantially as described.
- 45 In testimony whereof, I have hereunto set my hand.

JULIAN KENNEDY.
